No 53

J. J. Pathbone, assignee of
J. J. Pathbone assignee of

J. E. THOMAS' DESIGN FOR AN AIR TIGHT COOKING STOVE.

Patented July 10th 1846.

Drawn by W. N. Ellmann, Albany, N.Y.

Des. 53

John E. Thomas, (Assignor to Mr. T. Rathbone) Albany, N.Y.
Letters Patent (Design No. 53) dated 10th July 1846.

The Schedule referred to in these Letters Patent, and
making part of the same

To all whom it may concern:

Be it known that I, John E. Thomas of Albany,
in the County of Albany, and State of New York, have invented or produced
a new Design for an airtight Cooking Stove, and I do hereby declare that
the accompanying drawing is an accurate delineation and representation
thereof

The front of my stove exhibits a row of semi-
columns supported an ornamented architrave. The spaces between the
columns are filled with "dice-work" or diamond cutting. The panels &c
upon the sides are also filled with dice work. Both sides are alike,
except that the panel corresponding to aa is upon the opposite side of the
same height as bb and the narrow panel corresponding to cc is contin-
ued across the whole side without break. The back is plain. What
I claim as my invention and desire to secure by Letters Patent is the
combination and arrangement of ornamental figures and
the conformation of parts herein described and represented,
forming a design for an ornamental airtight
